UNITED STATES PATENT OFFICE.

WILLIAM J. BOHAN, OF ST. PAUL, MINNESOTA.

LAMP.

1,273,994.

Specification of Letters Patent. Patented July 30, 1918.

Application filed October 5, 1917. Serial No. 194,925.

To all whom it may concern:

Be it known that I, WILLIAM J. BOHAN, a citizen of the United States, and resident of St. Paul, county of Ramsey, and State of Minnesota, have invented certain new and useful Improvements in Lamps, of which the following is a specification, and which are illustrated in the accompanying drawings, forming a part thereof.

10 The invention relates to lamps in which the illuminating agent is an incandescent bulb, or equivalent device, and in which the bulb is located within a projecting reflector.

The object of the invention is to provide 15 improved means for focusing the bulb with reference to the reflector; and it consists in a structure such as is hereinafter described and as illustrated in the accompanying drawings, in which—

20 Figure 1 is a longitudinal section through the lamp; and

Fig. 2 is a sectional view on the line 2—2 of Fig. 1.

The lamp comprises a casing or shell 10, 25 here shown as bowl shaped and having a hollow stem 11 which is externally threaded. The lamp may be supported by any suitable means, such as a bracket-arm 12 secured to the shell. A projecting reflector 13 is 30 housed within the shell, and is apertured at its inner end, as shown at 14, to accommodate the base 15 of an incandescent bulb 16.

To the base 15 is suitably attached a cap 17 fitting over the stem 11, this attachment 35 being preferably by means of threaded engagement with a tubular stem 18 projecting inwardly from the cap 17, and through which the leading-in wires 19 may be conveniently entered.

40 The annular flange 20 of the cap 17 is secured to a collar 21 in threaded engagement with the stem 11 by means of annularly-arranged and equally spaced adjusting screws 22, 23, 24 and 25. The diameter of the annular flange 20 is sufficiently greater than 45 that of the collar 21 to permit lateral adjustment of the cap through the agency of the adjusting screws. These screws have their inner ends rounded, as indicated at 26, to

50 engage an annular groove 27 in the periphery of the collar 21. Jam nuts, as 28, may be mounted upon the adjusting screws to engage the outer face of the flange 20.

The described construction provides for 55 the universal adjustment of the bulb 16 with reference to the reflector 13. By turning up

one of a pair of diametrically disposed adjusting screws and turning back the other screw of the same pair, the cap 17, and with it the bulb 16, may be moved laterally. 60 The members of the other pair of screws will, of course, be set up tightly against the collar after such adjustment, in order to securely bind the parts together. By shifting the collar 21 upon the stem 11, the cap 65 and bulb may be axially adjusted. The two adjustments, therefore, permit the locating of the bulb at any point within the chamber of the reflector, thereby securing an accurate focus of the lamp.

70 Incandescent bulbs lack uniformity of construction, the filament of whatever formed, being differently positioned in many instances. Adjustment becomes necessary where, as in locomotive headlights, high efficiency is required. Readjustment is frequently necessary owing to a tendency of the filament to sag when heated, as indicated by dotted lines in Fig. 1.

75 While a preferred embodiment of the invention is illustrated, various structural changes may be made without departing from its scope.

I claim as my invention—

80 1. In a projecting lamp, in combination, 85 a shell having an externally threaded tubular stem, a reflector housed within the shell and having an aperture in its inner end, an incandescent bulb located within the reflector, the base of the bulb extending through the aperture thereof, a collar in threaded engagement with the stem of the shell, a cap attached to the base of the bulb and having a flange surrounding the collar and spaced apart therefrom, and adjusting screws in threaded engagement with the flange and bearing upon the collar.

90 2. In a projecting lamp, in combination, 95 a shell having an externally threaded tubular stem, a reflector housed within the shell and having an aperture at its inner end, a cap overlapping the stem of the shell and having an axially tubular stem entering and

of less diameter than the stem of the shell, an incandescent bulb located within the reflector and having its base attached to the tubular stem of the cap, a collar in threaded engagement with the stem of the shell, and adjusting screws connecting the cap with the collar.

100 3. In a projecting lamp, in combination, 105 a shell having an externally threaded tubu-

lar stem, a reflector housed within the shell and having an aperture at its inner end, an incandescent bulb located within the reflector, the base of the bulb extending through 5 the aperture thereof, a collar in threaded engagement with the stem of the shell, and a bulb carrier secured to the collar and being laterally adjustable with reference thereto.

4. In a projecting lamp, in combination, 15 a shell having a tubular stem, a reflector housed within the shell and having an aperture at its inner end, an incandescent bulb located within the reflector, the base of the

bulb extending through the aperture thereof, a collar mounted and axially adjustable on 15 the stem of the shell, and a bulb carrier secured to the collar and laterally adjustable with reference thereto.

5. In a lamp support, in combination, a tubular stem, a collar threaded upon the 20 stem, and a cap having a socket for receiving a lamp base and being secured to the collar and laterally adjustable with reference thereto.

WILLIAM J. BOHAN.
